UNITED STATES PATENT OFFICE

164,209

FISHERMAN'S UTILITY TOOL

William A. Uttz, Fort Worth, Tex.

Application February 16, 1951, Serial No. 14,234

Term of patent 14 years

(Cl. D31—4)

To all whom it may concern:

Be it known that I, William A. Uttz, a citizen of the United States of America, residing at Fort Worth, in the county of Tarrant and State of Texas, have invented a new, original, and ornamental Design for a Fisherman's Utility Tool, of which the following is a specification, reference being had to the accompanying drawing, forming part thereof.

Figure 1 is a side elevational view of a fisherman's utility tool embodying my new design.

Figure 2 is a top plan view of the device.

Figure 3 is an inverted plan view of my new design.

Figure 4 is a front end view of the tool.

Figure 5 is a back end view of the device, and

Figure 6 is a perspective illustration of the fisherman's utility tool showing the cover raised and the tape and scale hook extended.

I claim:

The ornamental design for a fisherman's utility tool, substantially as shown.

WILLIAM A. UTTZ.
